ABRADING TOOL

William A. Reed, Beverly, Mass., assignor to
 United Shoe Machinery Corporation, Paterson,
 N. J., a corporation of New Jersey

Application February 21, 1931, Serial No. 517,500

23 Claims. (Cl. 51—194)

This invention relates to abrading tools and is herein illustrated as embodied in a shoe-bottom-scouring roll of the type disclosed in United States Letters Patent No. 1,014,094, granted 5 January 9, 1912 upon the application of W. A. Reed. The abrading tool disclosed in the above-mentioned patent consists of a tool body adapted to be mounted upon a shaft and preferably provided with a yieldable periphery to support 10 an abrasive cover which may consist, for example, of sandpaper, although abrasive covers having cloth bases are frequently employed and the use of emery and other artificial grits in place of sand is common. The abrasive cover is 15 wrapped about the tool, and its ends are secured to the tool by a clamping device which clamps both ends of the abrasive cover simultaneously to the tool. The clamping device disclosed in the above-mentioned Letters Patent consists of 20 a plurality of clamping members disposed along the length of the roll and provided with mechanism for actuating all of them simultaneously.

Present day tendencies in the art of shoe scouring point to the desirability of using thinner sandpaper and abrasives of finer grit, and in running the roll at higher speeds of rotation. The thinner the sandpaper and the lighter the 25 glue coating which holds the abrasive material, the greater the degree of flexibility of the sandpaper, and the greater its capacity for yielding readily to the contour of the work. Thin sandpaper with fine abrasive material can be maintained in relatively steady and continuous engagement with the work without vibration or 30 bouncing of the work. The use of such an abrasive covering, especially upon a high-speed roll, results in an improved finish, imparting a uniform soft velvety surface to the work while shortening the time required to perform the 35 operation. Lighter sandpapers, however, are more subject to tearing, and, in speeding up the rotation of the roll, difficulties in the way of securing proper balance become increasingly apparent. One of the problems that arises relates to 40 the securing of the abrasive covering to the roll in such a way as to minimize any tendency to tear, and by instrumentalities which comprise a minimum of moving parts likely to throw a high-speed roll out of balance.

An object of the invention is to provide an improved rotary abrading tool embodying, among other advantages, suitability for high speed work. In accordance with this object, a feature of the invention consists in the combination of 45 an abrasive cover surrounding a tool body with

one end of the abrasive cover secured in overlapping relation to the other end, and a hook covered by the overlapping end of the abrasive cover for clamping the overlapped end to the tool body. The hook which secures the overlapped end of the abrasive cover is thus kept out of contact with the work. In the illustrated construction, the overlapping end of the abrasive cover is secured independently of the overlapped end, enabling the abrasive cover to be 5 drawn tightly and thus fitted accurately to the tool body, regardless of any departure of the tool body from a specified diameter. Being thus accurately fitted under tension, the abrasive cover grips the tool body tightly at all points, 10 and is thus held by direct frictional engagement with the tool body over its entire area against the frictional drag of the work, with the result that no great amount of stress is developed at any one point of the cover by reason 15 of the drag of the work. Localization of stress in the cover at the points of clamping, and the resulting tendency to tear at such points, are thereby minimized, while at the same time any considerable number of clamping devices to distribute such stress is rendered unnecessary. The use of relatively few clamping devices facilitates the attainment of perfect balance of 20 the abrading tool at high speeds, and it also minimizes the flattening effect upon the yieldable surface of the tool body which results from the localization of pressure of a large number 25 of closely adjacent clamping devices. The abrasive cover, which is secured upon the tool in the manner above-described, may, as in the illustrated scouring roll, be formed with V-shaped ends which are respectively salient and re-entrant. This form of cover presents an advantage in disposing the line of overlapping in an oblique relation to the roll, and it also insures 30 that all portions of the cover will be under tension and will be supported circumferentially of the roll against the frictional drag of the work, as will later be more particularly pointed out. Moreover, covers of the form under consideration 35 need be supported at relatively few points against the frictional drag of the work, thereby minimizing the number of devices which ordinarily are required to secure abrasive covers to their rolls and which render it difficult to maintain the rolls in proper balance at high speeds. 40

These and other features of the invention will be described as embodied in an illustrative machine and pointed out in the appended claims.

Referring now to the accompanying drawings, 45

Fig. 8 is an exploded perspective view of a modified form of roll; and 25

Fig. 9 is a perspective view of an abrasive cover for the roll shown in Fig. 8. 30

Referring to Figs. 1 and 2, a cylindrical drum or shell 10 which constitutes the foundation of the roll body has rigidly secured to each end thereof, by screws (not shown), a head 12 which is in the form of an annular disk. Extending 35 into the head 12 at the central opening thereof is a sleeve 14 having at its outer end and beyond the end of the drum 10 an annular flange 16. In the flange 16 is formed a notch 18 to provide access to a set-screw 20 whereby the sleeve 14 40 may be clamped to a shaft 22 upon which the abrading roll is to be mounted. In the illustrated roll the drum 10, the head 12 and the sleeve 14 are all composed of aluminum, which, because of its relative lightness, will tend to 45 minimize the vibration due to any slight lack of balance when the roll is rotated at high speed. Surrounding the sleeve 14 and filling up the space between the head 12 and the flange 16 is an annular disk of felt 24 having a diameter 50 somewhat greater than the external diameter of the drum 10. A shoulder 17 on the sleeve 14 abuts the head 12, and three screws 19 threaded into the head 12 and extending through the felt disk 24 and the flange 16 serve to hold the 55 sleeve 14 in endwise clamping engagement with the head 12. Except as hereinafter noted, the construction of each end of the roll is like that of the other, and the description of one end will be sufficient. Referring to Fig. 6, a relatively 60 narrow strip of paper 26 is wrapped helically about the drum 10 and is pasted thereupon. The ends of the strip 26 are oblique, the strip being in the form of a rhomboid. These oblique ends are disposed at such an angle as to 65 cause them to abut the felt disks 24 respectively when the paper strip 26 is in position upon the drum 10. The sides of the paper strip 26 abut each other so as not to present ridges or depressions. After the paper strip 26 has thus been applied to the drum 10, a strip 28 of flannel of 70 about the same size and shape as the paper strip 26 is wrapped helically upon the paper strip 26 in a direction opposite thereto and is pasted thereupon with its two sides abutting each other. Upon the flannel strip 28 are wrapped successively a plurality of relatively wide flannel strips 30, about eight in number, of rhomboid form. The oblique ends of the flannel strips 30 abut the felt disks 24 respectively, and 75 the sides of each strip abut each other so as not to leave ridges or depressions. The first flannel strip 30 is wrapped helically in a direction opposite to that of the relatively narrow flannel strip 28, and each succeeding flannel strip 30 is wrapped helically in a direction opposite to that of the strip immediately beneath it. The strips 30 may conveniently be applied by pasting with a latex cement first one end of each strip 30 to the strip immediately beneath it, then wrapping the strip 30 under moderate tension about the drum 10, and then similarly pasting the opposite end. After all of the strips 30 have thus 80 been secured in position, they may be further secured at each end of the roll by stitching them to the felt disks 24 respectively. Such stitches are shown at the left-hand end of the roll in Figs. 6 and 7. The strips 28 and 30, in the illustrated roll, are of wool flannel, and they may advantageously be subjected to a partial shrinking before applying them to the roll in order to 85 give them the most desirable character and degree of resilience. The roll body, when complete, will appear as shown in Fig. 7. 90

Surrounding the periphery of the roll body is an abrasive cover 32 having a V-shaped end 34 which is salient and an opposite V-shaped end 36 which is re-entrant. The sides of the abrasive cover 32 are straight and parallel to each other, and the ends 34 and 36 are so formed as to be parallel to each other when the abrasive 95 cover 32 is stretched out flat and also when it is applied to a roll, as will be evident upon reference to Fig. 1. The particular type of abrasive sheet material may be selected with reference to the character of the finishing or 100 scouring operation to be performed. In the illustrated roll, for example, the cover 32 consists of a paper base with a glued surface covered with a grit composed of silicon carbide. At the vertex of the salient end 34 is formed a 105 notch 38 the purpose of which is to receive a T-shaped clamping hook 40 for clamping this end of the abrasive cover against the roll body. The clamping hook 40 extends lengthwise with respect to the roll and is mounted at its central 110 portion upon a stem 42. Adjacent to each end of the clamp member 40 is a rounded protuberance 44 to insure a positive gripping of the abrasive cover. The protuberances 44 may conveniently be obtained by the use of rivets having 115 rounded heads. The stem 42 is carried by a plunger 46 which reciprocates in a guideway 48 formed in a boss 50 of a carrier disk 52. The external diameter of the disk 52 is equal to the 120 internal diameter of the drum 10, and the periphery of the disk 52 is flanged to accommodate 125 screws 54 whereby the disk 52 is secured to the drum 10. An axial opening 56 is formed in the disk 52 to enable the latter to clear the shaft 22, as shown in Fig. 2. The guideway 48 is substantially radial with respect to the roll body so 130 that outward movement of the plunger 46 raises the flange 40 to facilitate the introduction of an abrading cover 32, and inward movement of the plunger 46 serves to bring the clamp 40 into 135 operation to secure the end of the cover 32 to the roll body. To provide for actuation of the clamping mechanism a slot 58 (Fig. 4) is provided in the plunger 40 and a cam roll 60 is mounted in the plunger 46, bridging the slot 58. An actuating rod 62 is disposed lengthwise of 140 the roll and has an inclined cam surface 64 formed upon one of its ends for engaging the roll 60. Longitudinal movement of the rod 62 in one direction will serve to urge the plunger 145 46 inwardly and to bring the clamp 40 into operation. A helical spring 66 is positioned between the plunger 46 and the base of the guideway 48 for normally urging the clamp 40 outwardly. Another helical spring 68 surrounds 150 the plunger 46. 155

the rod 62 and is interposed between a boss formed on the disk 52 and a pin 70 which is inserted in the rod 62. The spring 68 serves normally to urge the rod 62 toward unclamping position. The opposite end portion of the rod 62 extends through holes formed in the head 12, the felt disk 24, and the flange 16, respectively, this end of the rod 62 being rounded, as indicated at 76. The instrumentalities whereby reciprocation of the rod 62 may be effected will be described presently.

After the salient end of the abrasive cover 32 has been secured by the clamp 40, the abrasive cover is pulled taut and is wrapped about the roll body. While the abrasive cover 32 is thus under tension, its free end 36 is secured by means of another and independently operable clamping device now to be described. Formed in each of the flanges 16 is a slot 78 which constitutes a guideway for a pair of clamping members 80 and 82. The slot 78 does not intersect the axis of the roll but is offset from it. In other words, the slot 78 is non-radial. The clamping member 80 is provided with a clamping hook or jaw 84 which extends substantially in a direction parallel to the axis of the roll body and which overlies the periphery of the roll body. The member 80 is also provided with an actuating stem 86 which is substantially parallel to the axis of the roll and which extends away from the end of the roll body. The clamping member 82 is shaped similarly to the clamping member 80 and underlies the clamping member 80. Its actuating stem is designated as 88. A rounded protuberance 89 is formed in the under surface of the clamping jaw 84 and registering therewith is a depression 91 formed in the jaw of the clamping member 82. The depression 91 may conveniently be formed by a stamping operation. The protuberance 89 and the depression 91 enable the clamping jaws to grip the abrasive cover firmly without punching a hole in it.

Actuation of the clamp 40 and of the jaws 80 and 82 at one end of the roll body is effected by means of a cam 90 in the form of a disk mounted for rotation about the axis of the roll body. In order to facilitate registry of the cam 90 with the roll body, the sleeve 14 is provided with an annular flange 92 adapted to engage a recess 94 formed in the cam 90. The cam 90 is held against axial movement relatively to the roll body by means of a screw 96 which extends through a slot 98 concentric with the cam 90, the screw 96 being threaded into an opening 100 formed in the flange 16. A concentric groove 102 is formed in the cam 90 and in this groove is positioned a cam member of relatively hard steel having an inclined face 104 adjacent to one of its ends, the remaining operative portion 106 of the cam member presenting an inactive substantially radial face. Another cam groove 108 is formed in the cam disk 90. The cam groove 108 has a portion 110 which is concentric with the axis of the cam 90 and another portion 112 which inclines inwardly at a relatively sharp angle to the radius. A third cam groove 114 is formed in the disk 90. The cam groove 114 has a concentric portion 116 and an inwardly inclined portion 118.

Assuming all the clamps to be in their unclamping positions and the cam slot 90 to be secured upon the end of the roll body, it is apparent that the rounded outer end 76 of the rod 62 will extend into the concentric groove 102

without engaging the inclined face 104, or possibly engaging the most depressed portion of this inclined face. The actuating stem 86 of the outer clamping member 80 will extend into the cam groove 108 and will be adjacent to the closed end of the concentric portion 110 thereof. The actuating stem 88 of the inner clamping member 82 will extend into the cam slot 114 and will be adjacent to the closed end of the concentric portion 116 thereof. Upon rotation of the cam disk 90 the inclined face 104 will force the actuating rod 62 toward the left, as viewed in Fig. 2, causing the clamp 40 to be drawn inwardly to clamping position. Upon further rotation of the cam disk 90 the inactive surface 106 of the cam member will ride upon the end of the rod 62 and thus maintain the clamp 40 in clamping position. As the cam 90 is thus further rotated, the actuating stem 86 of the clamp 80 will engage the inclined portion 112 of the cam groove 108, causing the clamping jaw 84 to be drawn inwardly until it clamps the abrasive cover against the corresponding jaw of the inner clamping member 82. Thereupon the actuating stem 88 of the inner clamping member 82 will engage the inclined portion 118 of the cam slot 114, and both of the clamping jaws will be drawn down with the abrasive cover gripped between them. It is desirable to provide for clearance between the actuating stems 86 and 88 and the sides of their respective cam slots, leaving a certain amount of play or lost-motion to each of the clamping members. To insure gripping of the abrasive cover notwithstanding such lost-motion, the flange 16 is bored to receive a compression spring 79, the bore constituting, in effect, an extension of the slot 78. The spring 79 urges the inner clamping member 82 outwardly as far as permitted by the cam slot 114, causing the inner clamping member 82 to grip the abrasive cover resiliently against the outer clamping member 80. The jaws of the clamping members 80 and 82 (Fig. 6) extend over the periphery of the felt disks 24, but they are not long enough to extend over the drum 10 and the flannel covering, so that the drum 10 and the relatively thin flannel covering will not interfere with the retraction of the jaws. The felt disks 24 are notched at their peripheries as indicated at 25, but the notches are not deep enough to accommodate the full retraction of the clamping jaws, so that when the jaws are fully retracted to secure the abrasive cover, the disks 24 will be under compression and will thus assist the springs 79 in resiliently supporting the lower clamping jaw against the pressure of the upper clamping jaw. When the jaws are fully retracted, they are within the periphery of the roll. The cam disk 90 at the left-hand end of the roll is in all respects similar to the cam disk 90 at the right-hand end except that the cam groove 102 and the hardened steel cam member within the slot are omitted. Also, the cam elements of the left-hand disk 90 are reversed in direction so that both disks may be turned in the same direction with like effect. Suitable holes 120 are formed in each of the flanges 16 and in each of the cams 90 for the purpose of distributing the weight of the material so as to insure proper balance.

In applying the abrasive cover 32 to the roll, the operator first fits the recess 38 of the abrasive cover about the stem 42 of the central clamping device and rotates the right-hand

cam disk 90 sufficiently to bring the clamp 40 down firmly into clamping position. The salient end of the abrasive cover thus being firmly secured to the roll body, the operator tucks the edges of the abrasive cover under the jaws of the lower clamping members 82, and he then wraps the abrasive cover about the roll and tensions it about the roll as tightly as he can. Power is, of course, shut off from the machine 10 at this time, and the shaft 22 may be locked against rotation to hold it against the pull of the operator upon the abrasive cover. He then inserts the corners of the re-entrant end of the abrasive cover between the jaws of the 15 clamping members 80 and 82. Upon further rotation of the right-hand cam disk 90 and upon rotation of the left-hand cam disk 90 the jaws of the clamping members grip between them the abrasive cover and also, by reason of the non- 20 radial disposition of the slots 78, they pull the re-entrant end of the abrasive cover in a direction having a circumferential component, thereby further tensioning the abrasive cover. Furthermore, the under surfaces of the jaws of the 25 lower clamping members 82 grip the edges of the abrasive cover adjacent to the salient end thereof.

In Fig. 8 is shown a modified form of roll which differs from the above-described form 30 only in certain particulars which will now be pointed out. The body structure of the modified form of roll is substantially the same as that of the roll illustrated in Fig. 1. The central clamping member, however, is omitted in 35 the form of roll now under consideration. In this form of roll the end flanges 16 are provided with radial slots 178 which constitute guideways for inner and outer clamping members 180 and 182 which are similar to the 40 clamping members 80 and 82, respectively, the clamping member 180 being provided with an actuating stem 186 and the clamping member 182 being provided with an actuating stem 188. A cam disk 190, which is similar to the cam 45 disk 90 except for the omission of the slot 98 and the groove 102, is provided for actuating the clamping members 180 and 182. The cam disk 190 has formed in it a cam groove 208 and a cam slot 214 respectively. Both of these cam 50 elements are spiral in relation to the axis of the cam disk, the groove 208 at its outer end portion 300 being more sharply inclined outwardly than the remaining portion of this groove. The cam disk 190 is held against axial 55 movement away from the flange 16 by means of a screw 302 which extends through the cam slot 214 and is threaded into the actuating stem 188, a washer 304 being provided to prevent the cam disk from slipping off. The cam disks 190 60 at each end of the roll body are identical except for the fact that the cam slots in one of them extend in reverse spirals with respect to the other. This arrangement affords the convenience of enabling both cam disks to be 65 turned in the same direction to effect clamping or unclamping. An abrasive cover 132 having a salient end 134 and a re-entrant end 136 is provided for this form of roll. No notch is provided at the vertex of the salient end of the 70 cover 132 but the margin 206 of the under surface of the salient end is coated with adhesive for a purpose which will appear as the description proceeds. The margin 207 of the outer surface of the re-entrant end 136 is also coated 75 with an adhesive. The abrasive cover 132 is

applied upon the roll illustrated in Fig. 8 by first inserting the corners of the re-entrant and between the clamping members 180 and 182 at each end of the roll body. Upon rotation of the cam disks 190 the outer clamping member 180 is retracted more rapidly than the inner clamping member 182 by reason of the fact that the end portion 300 of the cam groove 208 is more sharply inclined than the corresponding portion of the cam slot 214. This causes the clamping 10 jaws to close, and further movement of the cam disk 190 serves to embed the clamping jaws into the felt disk 24. The re-entrant end of the cover 132 now being securely clamped upon the roll body, the operator wraps the abrasive cover 15 about the roll body with as much tension as he can and, after moistening the adhesive-covered margins 206 and 207, he presses the salient end of the abrasive cover firmly down and pastes it upon the re-entrant end. The adhesive upon 20 the margins 206 and 207 may be glue of a character similar to that of the glue which holds the grit upon the abrasive cover, enabling the various layers of glue to coalesce and form an effective bond between the overlapping edges of 25 the paper. It will be noted that the abrasive covers 32 and 132 are both perforated as indicated at 210. The purpose of this is to enable air which has been entrapped beneath the cover to escape as the work presses down upon the 30 cover. This avoids any likelihood of the entrapped air bulging the cover in advance of the work. The perforations 210 also permit air to enter immediately after each portion of the 35 roll passes the work. By thus eliminating the effects of air pressure, they enable the flannel covering above described to exert its natural resilience. Perforations are especially desirable in a cover such as the cover 32 which is adapted to be clamped at the vertex of its salient end, 40 for in the absence of such perforations the clamping of the cover at this point would tend to prevent the retreat of an air pocket and the hard pocket of compressed air would result in a bumping effect upon the work. 45

The advantages in the use of a cover having salient and re-entrant ends in combination with cover-securing devices of the type above described are several. In the first place, they enable the line of discontinuity between the 50 two ends of the abrasive cover to be presented obliquely to the work, thereby avoiding such shock as would result from the line of discontinuity striking squarely against the work. In the second place, they enable the pull occasioned by the drag of the work against the abrading surface to be transmitted obliquely to the clamp 40, as in the form disclosed in Fig. 1, and to the clamping devices 180 and 182, as in the 55 form shown in Fig. 8. It is thus apparent in both of these forms that there is no portion of the abrasive cover but what is able to transmit its portion of the drag of the work to its clamping devices in a direction which has a circumferential component. In other words, no portion 60 of the cover is unsupported circumferentially against the drag of the work. Furthermore, this construction insures the distribution of the inherent tension of the cover throughout all portions of the cover, leaving no portion 65 untensioned. The salient and re-entrant form of cover presents a particular advantage in the form of roll illustrated in Fig. 8. In this form of cover the overlapping ends, together with the adhesive material which secures them together, 70

constitute a very effective means for taking up the drag occasioned by the work, and thereby reinforcing the cover by enabling it to withstand this drag, and thereby eliminating any tendency of the cover to bulge. The overlapped end 136, while it does not function as an abrading surface, does function, together with the adhesive on the margin 206, as a reinforcing member to transmit the drag of the work directly to the 10 clamps 180 and 182. Because of the V shape of this reinforcing member, the drag of the work will set up a direct tension in it rather than a stress tending to twist or distort the cover.

Having described my invention, what I claim 15 as new and desire to secure by Letters Patent of the United States is:—

1. An abrading roll comprising a roll body, an abrasive cover surrounding said roll body with one end of said abrasive cover overlapping the 20 other end, clamps extending over the periphery of said roll body adjacent respectively to each end of said roll body for securing one end of said abrasive cover to said roll body, a clamp for securing in position the opposite end of 25 said abrasive cover, and operating means for said clamps constructed and arranged to enable one end of the abrasive cover to be clamped in position independently of the other end.

2. An abrading tool comprising a tool body, 30 an abrasive cover surrounding said tool body with one end of said abrasive cover secured in overlapping relation to the other end, and a T-shaped clamp overlapping the working surface of the tool body and covered by the overlapping end of the abrasive cover for clamping the overlapped end of the abrasive cover to said 35 tool body.

3. An abrading roll comprising a roll body, an 40 abrasive cover of sheet material surrounding said roll body and having V-shaped ends which are respectively salient and re-entrant, a hook for clamping the vertex of the salient end of said abrasive cover against said roll body, and means for securing the side corners of the re-entrant end of said abrasive cover to said roll 45 body with the re-entrant end overlapping the salient end and covering said hook.

4. In an abrading roll, a roll body, a pair 50 of clamping hooks extending over the periphery of said roll body adjacent to the ends respectively of the roll body for securing one end of an abrasive cover, and a third hook carried by said roll body at a point spaced a substantial distance lengthwise and circumferentially of said 55 roll body from the two first-mentioned clamping hooks for clamping the other end of the abrasive cover against the periphery of the roll body.

5. In an abrading roll, a roll body, a plurality 60 of clamping devices displaced from each other both axially and circumferentially with respect to said roll body for securing an abrasive cover to said roll body, and means constructed and arranged to operate said clamping devices in succession.

6. In an abrading roll, a roll body, a clamping 65 device disposed between the ends of said roll body for securing a portion of an abrasive cover to said roll body, a clamping device disposed adjacent to one end of said roll body for securing another portion of the abrasive cover to said roll body, and mechanism including a cam constructed and arranged upon relative rotation with respect to said roll body to operate said clamping devices in succession.

7. In an abrading roll, a roll body, a clamping device disposed midway between the ends of said roll body for securing the mid-portion of one end of an abrasive cover to said roll body, a pair of clamping devices disposed adjacent to the ends respectively of said roll body for securing the corners of the opposite end of the abrasive cover to said roll body, mechanism including a cam constructed and arranged upon relative rotation with respect to said roll body 10 first to operate the first-mentioned clamping device and then to operate one of the end-clamping devices, and means for operating the other end-clamping device.

8. In an abrading roll, a roll body, a clamping hook for securing an abrasive cover upon said roll body, a spring normally urging said clamping hook outwardly from said roll body to facilitate the insertion of the abrasive cover, and means including a wedge constructed and 20 arranged by lengthwise movement with respect to said roll body to move said hook inwardly to clamping position.

9. In an abrading roll, a roll body, a clamping hook for securing an abrasive cover upon 25 said roll body, mechanism including a rod extending lengthwise of said roll body for operating said clamping hook, and a cam constructed and arranged upon relative rotation with respect to said roll body to move said rod longitudinally 30 to operate said clamping hook.

10. In a rotary abrading tool, a tool body having a yieldable periphery, a clamping hook extending over the periphery of said tool body for securing an abrasive cover upon said tool body, and means for moving said clamping hook in a direction having both inward and tangential components relatively to said tool body to cause 35 said clamping hook to grip and tension the abrasive cover.

11. In a rotary abrading tool, a tool body having a yieldable periphery, a pair of clamping jaws extending over the periphery of said tool body for securing an abrasive cover upon said tool body, means for closing said clamping jaws 45 to grip the abrasive cover between them and for drawing said clamping jaws inwardly against the yieldable periphery of said tool body.

12. In a rotary abrading tool, a tool body, a pair of clamping jaws for securing an abrasive 50 cover upon said tool body, and means including a pair of cam elements operable respectively upon said clamping jaws to effect a relative closing movement of said jaws to grip the abrasive cover and to move said jaws both inwardly and circumferentially with respect to said tool body to tension the abrasive cover.

13. In a rotary abrading tool, a tool body, a pair of clamping jaws extending over the periphery of said tool body, an abrasive cover surrounding said tool body, said abrasive cover at a point adjacent to one of its ends extending between one of said clamping jaws and the periphery of said tool body, said abrasive cover also at a point adjacent to its opposite end extending between said clamping jaws, and means for closing and retracting said clamping jaws to clamp said opposite end portion of the abrasive cover between them and to clamp the first-mentioned end against the periphery of the tool 60 body.

14. In a rotary abrading tool, a tool body having a guideway extending inwardly in a direction offset from the axis of said tool body, a pair of clamping members slidable in said guideway 70

way for securing an abrasive cover upon said tool body, and means operable first to effect a relative clamping movement of said members and then to draw said members inwardly to tension 5 the abrasive cover.

15. In a rotary abrading tool, a tool body having an inwardly extending guideway, a pair of clamping members slidable in said guideway for securing an abrasive cover upon said tool 10 body, and a cam constructed and arranged first to effect a relative clamping movement of said clamping members and then to draw said clamping members inwardly.

16. In a rotary abrading tool, a tool body having a guideway extending inwardly in a direction offset from the axis of said tool body, a pair of clamping members slidable in said guideway for securing an abrasive cover upon said tool body, and a cam constructed and arranged 15 first to effect a relative clamping movement of said clamping members to grip the abrasive cover and then to draw said clamping members inwardly to tension the abrasive cover.

17. In a rotary abrading tool, a tool body, a pair of members mounted in said tool body constructed and arranged to clamp between them an abrasive cover for the tool body, and a cam mounted for relative rotation with respect to 20 said tool body, said cam having a pair of slots which are engaged by said clamping members respectively and which are shaped to cause relative closing of said clamping members.

18. In a rotary abrading tool, a tool body, a pair of members mounted in said tool body constructed and arranged to clamp between them an abrasive cover for the tool body, and a cam mounted for relative rotation with respect to 25 said tool body, said cam having a pair of slots which are engaged by said clamping members respectively and which are shaped to cause said clamping members first to grip a portion of the abrasive cover and then to draw the gripped portion of the abrasive cover inwardly with respect to said tool body as the cam is rotated 30 relatively to the tool body.

19. In an abrading roll, a roll body having a rigid core, a relatively thin flannel cover for 35 said core terminating short of the ends of the

roll body, a relatively thick felt cover at each of the ends of the roll body; said core having a relatively greater diameter beneath said flannel cover and a relatively less diameter beneath said felt covers, the external diameters of said flannel and felt covers being substantially equal, and a clamping hook at each end of the roll body extending over the adjacent felt cover for clamping an abrasive cover upon the roll body. 5

20. In a rotary abrading tool, a tool body having a rigid core, a yieldable cover for said core of relatively shallow depth and terminating short of the ends of said core, a yieldable cover of relatively greater depth adjacent to each end of said core, and clamping devices positioned adjacent to each end of said core and movable inwardly for securing an abrasive cover upon said roll body, said devices being adapted when in clamping position to lie within the peripheries of said covers of relatively greater depth 10 15 20 respectively.

21. A rotary abrading tool comprising a tool body, an abrasive cover wrapped around said tool body with the ends of the abrasive cover pasted together in overlapping relation, and means covered by the overlapping end of said abrasive cover for securing the overlapped end to said tool body. 25

22. An abrading roll comprising a roll body, an abrasive cover wrapped around said roll body with the ends of the abrasive cover pasted together in overlapping relation, and clamping devices adjacent respectively to each end of said roll body for securing the overlapped end of said abrasive cover to said roll body, said clamping devices being covered by the overlapping end of said abrasive cover. 30 35

23. An abrading roll comprising a roll body, an abrasive cover of sheet material surrounding said roll body, said cover having V-shaped 40 ends which are respectively salient and re-entrant, clamps extending over the peripheral surface of the roll body for securing the two corners of the re-entrant end of said covering to said roll body, and adhesive means for securing together the ends of said cover. 45
